Application November 15, 1957, Serial No. 48,483

Term of patent 7 years

(Cl. D3—11)

Fig. 1 is a front view of a glove showing my new design as it appears with the thumb turned downwardly against the lower portion of the glove; and

Fig. 2 is a rear view of the glove shown in Fig. 1 as it appears with the thumb turned upwardly.

The characteristic feature of my design resides in the combination on the glove disclosed of the specific contrasting stripe which extends downwardly and diagonally across the palm portion and terminates in a point midway of the back of the glove in association with an up-turned cuff, all as shown.

I claim:

The ornamental design for a glove, substantially as shown and described.
